Patented Aug. 22, 1922.

UNITED STATES PATENT OFFICE.

ANDREW W. GRAHAM, OF BUFFALO, NEW YORK.

SANITARY BOTTLE STOPPER.

1,426,728.

Specification of Letters Patent. Patented Aug. 22, 1922.

Application filed December 8, 1920. Serial No. 429,237.

To all whom it may concern:

Be it known that I, ANDREW W. GRAHAM, a citizen of the United States of America, residing at Buffalo, in the county of Erie 5 and State of New York, have invented certain new and useful Improvements in Sanitary Bottle Stoppers, of which the following is a specification.

This invention relates to bottle closures 10 and more especially to a sanitary bottle stopper.

It is well known that the ordinary paper or press board disk used to close milk bottles and the like is open to many objections. 15 In the first place such disks are difficult to remove without injury to the stopper, the point of a sharp instrument such as a knife or fork being usually employed for the purpose.

20 One important object of the invention is to provide an improved form of such stopper which can be removed without injury so that it may be replaced and continue to effectively perform its function.

25 Another objection inherent in a flat disk lies in the fact that such disks are subject to contact with the fingers on the side next to the bottle contents and there is thus contamination of the bottle contents if the stopper 30 be replaced after once opening the bottle.

A second important object of the invention is to provide an improved form of bottle stopper so shaped that it may be removed and replaced with a minimum of 35 danger from contact by the fingers or other objects with the portion coming in contact with the contents of the bottle.

40 Another serious objection to the usual press board disk is that it is necessarily lacking in flexibility since it can only have the requisite strength when made sufficiently rigid.

45 A third important object of the invention is the provision of a stopper having a flexible metallic reinforcement.

With the above and other objects in view, as will be hereinafter apparent, the invention consists in general of certain novel arrangements of details and formations of 50 parts hereinafter fully described, illustrated in the accompanying drawings and specifically claimed.

In the accompanying drawings like characters of reference indicate like parts in 55 the several views, and:—

Figure 1 is a perspective view of a bottle

showing one form of the improved stopper applied thereto.

Figure 2 is a transverse section through such a bottle neck and stopper. 60

Figure 3 is a view similar to Figure 2 but showing a modified form of the device.

Figure 4 is a section showing a second modification.

Figure 5 is a plan view partly broken 65 away showing one form of reinforcement.

Figure 6 is a view similar to Figure 5 but showing a second form of reinforcement.

In the form shown in Figures 1, 2 and 70

3 there is shown a container, such as a milk

bottle or other similar container, having a body 10 and provided with an internal shoulder 11 adjacent its mouth. The exterior of

the mouth in this form is provided with a plain bead or lip 12. In Figure 4 the ex- 75

ternal lip, in place of a simple bead as in the first form, is formed of two parts 13 and

14 so arranged as to provide a groove 15. The closure for each form consists of a central portion 16, here shown as a flat disk 80

like portion although it may be of any de- 85

sired shape. This central disk is surround- ed by a flange 17. Surrounding the flange

portion, whether of the type shown in Figure 2 or that shown in Figure 3, is a rim 85

portion shaped to fit the mouth and lip of

the bottle as shown at 18 and provided, when the device is used with such a bottle

as that of Figure 4, with an inwardly 90

pressed rib 19. The caps thus formed may

be made of ordinary press board treated or

not with paraffin without reinforcement but

I preferably make each cap or stopper in

three layers *a*, *b* and *c*, the outer layer *a* be- 95

ing of press board, the inner layer *c* being

of sanitary paper which may be a thin, 100

tough paraffin paper, and the central layer *b* being a metallic reinforcement such as the

reticulated tinfoil shown in Figure 5 or the

woven pliable wire shown in Figure 6. 105

The rim of any stopper formed in this

manner will be flexible so that the stopper

may be placed on the bottle and the rim

pressed or squeezed inward beneath the

bottle lip. Thus the device may be readily 110

removed, owing to the flexibility of the

channel shaped peripheral portion, with-

out injuring the sealing qualities of the stop- 115

per, and as readily replaced when desired.

Moreover, as only the under side of the cen-

tral portion ever is touched by the contents

of the bottle, and this part is never touched

by the user's fingers or, if laid down or dropped, by the surface whereon it is placed or falls, there is no danger of contaminating the bottle contents from such sources if the 5 stopper be used to reseal the bottle.

It will be noted that the forms shown in Figures 3 to 6 omit the outer layer A, the three layer type being only shown in Figure 2.

10 In applying this cap to bottles originally the application may be effected by suitable machinery in which case the caps may be cut and formed from a sheet of the material to be used. In this case the contour of the 15 blanks would preferably be hexagonal so that the blanks may be arranged in rows like the cells in a honeycomb thus effecting economy of the material.

Furthermore the center of each cap forming the part 16 may be stamped or pressed, either with or without heat, in such manner as to render this part very hard and practically to parchmentize it. This not only stiffens the center but renders it impervious 25 to moisture and expands it laterally so that the side walls 17 are kept firmly pressed against the inside of the bottle neck and leakage of the contents through capillary attraction is prevented.

30 There has thus been provided a simple and efficient device of the kind described and for the purpose specified.

It is obvious that many minor changes 35 may be made in the form and construction of the invention without departing from the material principles thereof. It is not therefore desired to confine the invention to the exact form herein shown and described but it is wished to include all such as come within 40 in the scope claimed.

Having thus described the invention, what is claimed as new, is:—

1. A stopper of the class described consisting of outer and inner layers of paper like material and an intermediate reinforcing layer of flexible metal all of said layers having coterminous edges whereby the edge portions of the stopper will be retained in shape by the reinforcement after forcible 45 shaping to fit a bottle.

50 2. A stopper of the class described consisting of outer and inner layers of paper like material and an intermediate reinforce-

ing layer of reticulated flexible metal all of said layers having coterminous edges whereby the edge portions of the stopper will be retained in shape by the reinforcement after 55 forcible shaping to fit a bottle.

3. A stopper of the class described consisting of outer and inner layers of paper like material and an intermediate reinforcing layer of reticulated tinfoil all of said layers having coterminous edges whereby the edge portions of the stopper will be retained in shape by the reinforcement after 60 65 forcible shaping to fit a bottle.

4. A stopper of the class described formed of paper like material and provided with a metallic reinforcement, the central portion being compressed and hardened to produce a 70 substantial parchmentization whereby flexure of the center of the stopper will be resisted after forcible insertion of said center in the mouth of a bottle.

5. A stopper of the class described consisting of outer and inner layers of paper like material and an intermediate reinforcing layer of flexible metal all of said layers having coterminous edges whereby the edge portions of the stopper will be retained in 75 80 shape by the reinforcement after forcible shaping to fit a bottle, the central portion being compressed and hardened to produce a substantial parchmentization.

6. A stopper of the class described consisting of outer and inner layers of paper like material and an intermediate reinforcing layer of reticulated flexible metal all of said layers having coterminous edges whereby the edge portions of the stopper will be retained in shape by the reinforcement after 90 95 forcible shaping to fit a bottle, the central portion being compressed and hardened to produce a substantial parchmentization.

7. A stopper of the class described consisting of outer and inner layers of paper like material and an intermediate reinforcing layer of reticulated tinfoil all of said layers having coterminous edges whereby the edge portions of the stopper will be retained in shape by the reinforcement after 100 105 forcible shaping to fit a bottle, the central portion being compressed and hardened to produce a substantial parchmentization.

In testimony whereof I affix my signature. 105
ANDREW W. GRAHAM.
